PROCESS OF MAKING SMOKELESS POWDER.

1,308,344.

Specification of Letters Patent.

Patented July 1, 1919.

Application filed May 2, 1916. Serial No. 94,946.

To all whom it may concern:

Be it known that I, FRANCIS I. DU PONT, a citizen of the United States, residing at Wilmington, county of New Castle, and State 5 of Delaware, have invented a new and useful Improvement in Processes of Making Smokeless Powder, of which the following is a full, clear, and exact description, reference being had to the accompanying drawings, which form a part of this specification.

In the manufacture of smokeless powder it is well known to partly remove the water from the nitrocellulose by wringing in a centrifugal machine, then displace the remaining water with alcohol by percolation with pressure to form a cake containing from 20 to 25 per cent. alcohol, then breaking up the same, and then mixing with the alcoholized nitrocellulose ether in amount 20 equal to about twice the amount of alcohol, and then transferring the product to a press to form it into strings.

The object of my invention is to modify the above process in such a way as to save 25 time in mixing, to avoid the formation of a hard cake when the nitrocellulose is freed from excess of one ingredient of the solvent, and to avoid the production of lumps of unmixed material in the finished product.

One of the features of my invention is the 30 mixing of the nitrocellulose first with the ether, which is used in greater quantity than alcohol, and later with the alcohol. This reversal of the old process possesses 35 a great advantage in that the excess of ether can be removed with but a small fraction of the pressure required to remove the excess of alcohol in the old process. It is also associated with other novel steps, whereby 40 by the above results are secured and whereby also the volume of ether to a given weight of nitrocellulose may be accurately predetermined.

To carry out my invention I have provided 45 a novel apparatus, an understanding of the construction and operation of which will enable the essential features of the process to be more readily comprehended. In the drawings:

Figure 1 is a side elevation, partly in section, of the major part of the apparatus. Fig. 2 is a similar view, somewhat diagrammatic, of the mixing machine. Fig. 3 is a side view of the hopper. Fig. 4 is an

end view of the drier. Fig. 5 is a partial longitudinal section of the drier.

The nitrocellulose is wrung in a centrifugal machine (not shown), as heretofore, to expel as much of the water as is practicable, say until it contains about 25 per cent. moisture. The nitrocellulose is then transferred to a hopper *a* having its bottom closed by an endless carrier *b*, which, with the roller *c*, transfers the nitrocellulose in a slow and measured stream from the hopper to the drier.

The drier is essentially a long stationary cylinder *d* through the axis of which extends a rotary power driven shaft *e* having spokes *f* to which are secured a worm *g* 70 extending close to the inner wall of the cylinder. The cylinder is supported on a frame work *h* inclosing a heated chamber through which extend heating pipes *i*. Warm air may also be introduced into the discharge 75 end of the cylinder through the pipe *d'* and caused to circulate through the same in the opposite direction to that of the travel of the nitrocellulose. The wall of the cylinder is made of very thin sheet metal so that in 80 the event of an explosion it will readily rupture.

The discharge end of the drying cylinder may have a discharge chute *j* provided with rotary feed blades *k* for delivering 85 the nitrocellulose without permitting escape of the warm air used for drying, into a funnel *m* opening into the top of a tank *o*. Within the funnel *m* is a power driven cork screw-like device *n*.

The tank *o* is maintained full of ether, which extends up into the funnel *m* and also into an overflow device *p*. Within the tank is a rotary agitator *q*.

The device *n* causes the dry nitrocellulose 95 to mix with the ether. During the feeding and drying operation the agitator *q* remains stationary. Thus the nitrocellulose settles to the bottom, and the pure ether displaced by the nitrocellulose escapes from 100 the tank by way of the overflow *p*.

After the tank *o* has received the maximum designed amount of nitrocellulose, the feeding mechanism is stopped and the agitator *q* started so as to thoroughly mechanically mix the nitrocellulose and ether, it being understood that the nitrocellulose is 105 not soluble in ether alone.

Communicating with the bottom of tank *o* is a tank *s*, communication between the tanks being controlled by a plug valve *r*. The tank *s* is similar in construction to the tank *o*, but is unprovided with an overflow. It does have, however, an agitator *t*, similar to agitator *q* in tank *o*. In the bottom of tank *s* is a spout *v*, controlled by a plug valve *u*, discharging into a press, the latter 10 comprising a cylinder *w* having a pivoted top and a piston *x* provided with a strainer.

A sample of known volume may be taken from tank *s* to ascertain the weight of nitrocellulose therein. It is thus possible to use 15 the press as a measure to determine a definite weight of nitrocellulose. By pressure to a calculated volume the press will deliver a definite weight of nitrocellulose wetted with a definite volume of ether.

20 The cakes formed in the press are then transferred to any suitable mixing machine. A mixer constructed on the principle of a bread mixing machine is preferable, such a machine being shown somewhat diagrammatically in Fig. 2, in which *y* represents the receptacle and *z*, *z*, two blades rotating therein in opposite directions, at different angular speeds. In this machine the predetermined quantity of alcohol, which should 25 equal one-half the volume of ether contained in the cake received from the press, is added gradually.

In the above description of the apparatus and its operation the several steps of the 30 process have been incidentally described with sufficient detail to enable the essential features of the process to be clearly understood. It is, however, unnecessary to employ mechanism of any particular construction to carry out the process, but the mechanism described presents features of decided utility and advantage.

The pressure required to eliminate the excess of ether is substantially less than is required in the old process hereinbefore mentioned to get rid of the excess of alcohol. The pressure being substantially less, a hard mass is not formed and no lumps of unmixed material are contained in the finished 45 product.

50 While I have referred to ether and alcohol as the liquids which together form a solvent for the nitrocellulose, it will be understood

that my invention comprehends the use of other liquids having respectively equivalent properties.

The drier herein described is the subject-matter of a separate application filed July 18, 1917, Serial No. 181,227.

Having now fully described my invention, 60 what I claim and desire to protect by Letters Patent is:

1. The process of manufacturing smokeless powder, which consists in first mixing nitrocellulose with ether, then expelling the 65 excess of ether with pressure, and then mixing the nitrocellulose with alcohol to form a gelatinous or colloidal mass.

2. The process of manufacturing smokeless powder, which consists in drying nitrocellulose, mixing it with ether, compressing the nitrocellulose to eliminate the excess of ether, and breaking up the compressed nitrocellulose and mixing it with alcohol to gelatinize or colloidize the nitrocellulose. 75

3. The process of manufacturing smokeless powder, which consists in drying nitrocellulose, conveying it to a body of ether, agitating the ether and nitrocellulose to effect their mixture, pressing successive fractional quantities of the entire mixture to expel therefrom the excess of ether, and then breaking up the compressed nitrocellulose and adding alcohol thereto. 80

4. The process of manufacturing smokeless powder, which consists in feeding the same to a body of ether and during said feeding driving off water by means of heat, agitating the ether and nitrocellulose to effect their mixture, pressing successive fractional quantities of the mixture to expel therefrom the excess of ether, and then breaking up the pressed cakes and mixing therewith alcohol. 85

5. The process of manufacturing smokeless powder, which consists in first drying nitrocellulose, then immersing the same in a body of ether and mechanically mixing it therewith, then compressing the nitrocellulose to expel the excess of ether, and then 90 mixing with alcohol the nitrocellulose which has been thus wetted with ether. 95

In testimony of which invention, I have hereunto set my hand, at Philadelphia, on this 27th day of April, 1916.

FRANCIS I. DU PONT.
